(57) **CLAIM**

The ornamental design for a rifle rest for a monopole, as shown and described.

DESCRIPTION

FIG. 1 is a side perspective view of a rifle rest for a monopole showing the claimed design.

FIG. 2 is a rear view of the rifle rest for a monopole illustrated in FIG. 1.

FIG. 3 is a front view of the rifle rest for a monopole illustrated in FIG. 1.

FIG. 4 is a right side view of the rifle rest for a monopole illustrated in FIG. 1.

FIG. 5 is a left side view of the rifle rest for a monopole illustrated in FIG. 1.

(Continued)

FIG. 6 is a bottom view of the rifle rest for a monopole illustrated in FIG. 1.

FIG. 7 is a top view of the rifle rest for a monopole illustrated in FIG. 1; and,

FIG. 8 is another side perspective view of the rifle rest for a monopole of FIG. 1 but in a stored or retracted position. The broken lines in the figures show portions of an environment that form no part of the claimed design.
